KARL REZNICEK, OF NEW YORK, N. Y.

FLUSHING VALVE.

Application filed September 28, 1921. Serial No. 503,862.

To all whom it may concern:

Be it known that I, KARL REZNICEK, a citizen of the United States, and resident of New York, in the county of New York and State of New York, have invented certain new and useful Improvements in Flushing Valves, of which the following is a specification.

This invention relates to flushing valves, its objects are to make a flushing valve of low manufacturing cost and of high efficiency for water closet bowls and other purposes.

In the accompanying drawings, forming a part hereof,

Fig. 1 is a vertical central section of a flushing valve embodying this invention, and

Fig. 2 a side elevation thereof, portions being broken away for greater clearness.

In the drawings, the upstanding casing 1 has at the lower end of its side wall an intake port 2 for connection of a feed water pipe, from which water under head flows into and through the casing.

The casing bottom has an outlet port 3 for connection with a discharge pipe.

Within the casing chamber is an upstanding, integral, tubular, water escape conduit 4 having an exterior diameter less than the interior diameter of the casing chamber. The chamber between the casing wall and this water escape conduit is indicated by 5 and extends upwardly above the upper end of the escape conduit part way to the top of the casing. The chamber of conduit 4 is indicated by 6. Within the upper portion of chamber 5 there is mounted a removable, upstanding water receiving cup 7 having in its side a water intake port 7^a of small diameter, whereby the upper portion of chamber 5 and the chamber 6^a of the cup are in constant communication. This cup 7 constitutes the main valve. The bottom of the cupped main valve is centrally provided with a water escape port enclosed by a valve seat 8. An exteriorly threaded tubular extension 9 from the valve seat and bottom of the cup extends downwardly into the upper end of chamber 6. A poppet valve having a disc

shaped body member 10 which has its under peripheral margin reduced at 11 to a lesser diameter than that of its top portion, is mounted on the upper surface of a gasket 12 of lesser diameter than that of the reduced valve body portion 11. The gasket

12 has a diameter sufficient to permit the gasket to be pressed on the valve seat for prevention of leakage when the valve body is seated. The gasket is mounted on the upper threaded end of a vertical valve stem 60 on which the valve body 10 is screwed, the gasket being clamped between the latter and the upwardly, conically flared portion 13 of the valve stem. The upper peripheral edge of the flared portion 13 is of a diameter 65 which permits it to be in sliding contact with the mouth wall of the dependent tubular extension 9 of the valve seat and bottom of the valved cup 7.

The valve body gasket and valve stem 70 are tiltable by lateral pressure on the dependent under end of the valve stem within the chamber 6, for unseating the valve. For this purpose the lower end of the casing is formed with a horizontal, tubular extension 75 1^a through which a valve stem tilting rod having an outer end flanged head 14^a projecting into the chamber 6 and into working contact with the valve stem shank. The outer end of the valve stem tilting rod 14, outwardly of the casing extension 1^a, is operated by a handle grip 15 which projects horizontally from the casing and is workable against the tension of a horizontal coiled spring 16 inwardly of the flanged head 14^a of the tilting rod 14 and enclosing the latter within the chamber of a hollow nut 17.

The open top of the casing is covered by a removal cap 18 having an exterior top nut 18^a for application of a wrench. This 90 cover cap is threaded to the casing at 19 and carries on its under side a centrally disposed, downwardly projecting stop pin 20, the upper end of which is secured to the cap at 20^a. The cupped main valve 7 has its bottom 95 resting on an annular gasket 21 which surrounds the dependent extension 9 of the cup and bears on the upper horizontal end of the water escape conduit 4. An annular gasket 22 is interposed between the cap 18 and the 100 upper end wall of the casing adjacent the threaded union of the cap and casing at 19. The under end of the stop pin 20 is slightly above the upper surface of the valve body 10. The upper end of the cupped main valve 7 has an annular flanged nut 23 screwed to it at 23^a the chamber 6 of the cupped main 105 valve being in constant communication with the chamber 24 of the cap through the annular gasket 22. The flange of the nut 23 is 110

indicated by 28^a and it clamps the inturned flange 33^a of a tubular gasket 33 against the upper end of the upstanding, open topped, cupped main valve. The lower portion of 5 the gasket 33 encloses the brim of the cupped main valve and the exterior wall of the gasket 33 together with the periphery of the flange 28^a are in sliding relation to the interior wall of the casing 1. The lower end 10 portion of the side wall of the cup 7 is conveniently provided with peripherally projecting abutments x, the outer surfaces of which are arced but are out of contact with the inner wall of the casing 1 in order to 15 form a series of restricted water passages x' between the under portion of chamber 5 below the bottom portion of the cup 7 and the upper portion of the chamber 5 where it surrounds the body of the cup 7 and finds 20 entrance through the port 7^a into the chamber 6^a of the cup.

The inward end of the valve stem tilting rod 14 is, within the chamber 6, provided 25 with an interiorly threaded nut 25, the open end of which projects outwardly and at 26 is threaded on the inwardly projecting tubular end of the spring containing nut 17 which is contained in the bore of the tubular casing extension 1^a. The tilting rod 14 ex- 30 tends through the nut 17. The outward end of the nut 17 is exteriorly threaded for connection at y with a chambered, handle-bar-carrying nut 17^a which, at y', has a threaded 35 connection with the bore of the casing extension 1^a.

The inwardly facing bottom wall of the chamber of the nut 17^a is concave and the half round head 27^a of the handle bar 27 bears rockingly on such concave wall. The 40 inward end of the head 27^a is flat and bears against the flat outward end wall of the flange head 14^a of the tilting bar 14. The handle bar 27 is provided inwardly of its 45 end with a shoulder against which the flanged end 28 of a sleeve on the handle bar is abutted. The handle grip 15 has its inward end fitted to this flanged sleeve 28, the handle bar 27 extending through an axial opening of the handle grip 15, the butt end 50 of which is held in place by a flanged butt end nut 29 threaded on the outer end of the handle bar 27.

Referring to the construction of the valve body as a whole, it is to be observed that 55 the reduced portion 11 of the valve body 10 has its under margin annularly overhanging the gasket 12; and that by the reduction in diameter of the under end of the valve body 10 its under margin overhangs annularly 60 the reduced portion 11. By this construction the tiltable valve body is given a step-up peripheral contour.

The operation of this flushing valve is as follows:

65 When it is installed and before water is

let on the tiltable valve seats itself by gravity. When the water under head has entered the intake port 2 it flows into the chamber 5 around the escape conduit 4 and rises thence slowly through the restricted 70 passages x' into the upper portion of the chamber 5 between the casing wall and the body of the cupped main valve; and thence flows slowly through the small port 7^a, gradually filling the chamber 6^a and rising 75 upwardly into the communicating cap chamber 24, whereby, in the chambers 24 and 6^a, which practically constitute one chamber, a pressure is built up and exerts 80 itself against the valve body 10 to hold the same firmly seated, the gasket 12 then being compressively forced against the valve seat and preventing leakage.

Whenever the handle trip is pulled down, or, in fact, moved in any direction, it is so 85 moved against a tension of the coiled spring 16 and cant the shank of the valve stem within the water escape chamber 6, thus slightly lifting an edge portion of the gasket off the valve seat. The water under pressure 90 in the chamber 6^a then tends to flow out. The cupped main valve is vertically reciprocable in reference to the upper end of the conduit 4; and the small port 7^a of restricted area is in a side wall of the cupped main 95 valve above the restricted passage x' between the lower portion of the cupped valve and the thereto opposed interior wall of the main casing.

What I claim is:

A flushing valve comprising in combination, a vertically chambered main casing having in its lower portion an upstanding tubular water escape conduit the periphery of which is spaced apart from the opposed interior wall of the casing; the casing wall and the wall of the escape conduit being integral with a tubular extension open at its outer end and opening into the water escape port; a vertically movable, cupped main 100 valve, seatable on the upper end of the tubular escape conduit above the said extension; the upper end of the cupped main valve being provided with a hollow nut and a gasket the peripheries of which are in sliding 105 relation to the interior wall of the upper portion of the casing; the side wall of the cupped main valve having a water intake port of restricted dimensions below said gasket and nut, and above its under end 110 portion; the under end wall of the cupped main valve having a water escape port communicating with said water escape conduit; and the peripheral wall of the under end portion of the cupped main valve being 115 dimensioned relatively to the thereto opposed portion of the main casing to form a restricted waterway between a chamber, the lower portion of which is around the water escape conduit and the upper portion of 120

100
